(57) **CLAIM**

The ornamental design for convertible wired or wireless earbud according to my invention, as shown and described herein.

DESCRIPTION

FIG. 1 is a perspective view of the ornamental design for a first embodiment of convertible wired or wireless earbud according to my invention;

FIG. 2 is a side view of the ornamental design for the first embodiment of convertible wired or wireless earbud according to my invention;

FIG. 3 is an opposing side view of the ornamental design for the first embodiment of convertible wired or wireless earbud according to my invention;

FIG. 4 is a front view of the ornamental design for the first embodiment of convertible wired or wireless earbud according to my invention;

FIG. 5 is a rear view of the ornamental design for the first embodiment of convertible wired or wireless earbud according to my invention;

FIG. 6 is a top view of the ornamental design for the first embodiment of convertible wired or wireless earbud according to my invention;

FIG. 7 is a bottom view of the ornamental design for the first embodiment of convertible wired or wireless earbud according to my invention;

FIG. 8 is a perspective view the ornamental design for a second embodiment of convertible wired or wireless earbud according to my invention;

FIG. 9 is a side view of the ornamental design for the second embodiment of convertible wired or wireless earbud according to my invention;

FIG. 10 is an opposing side view of the ornamental design for the second embodiment of convertible wired or wireless earbud according to my invention;

FIG. 11 is a front view of the ornamental design for the second embodiment of convertible wired or wireless earbud according to my invention;

FIG. 12 is a rear view of the ornamental design for the second embodiment of convertible wired or wireless earbud according to my invention;

FIG. 13 is a top view of the ornamental design for the second embodiment of convertible wired or wireless earbud according to my invention; and,

FIG. 14 is a bottom view of the ornamental design for the second embodiment of convertible wired or wireless earbud according to my invention.

The broken lines are illustrative of environmental structure only and form no part of the claimed design.
